METHOD OF MANUFACTURING ORNAMENTAL FACEPLATES FOR PENKNIVES AND THE LIKE

Maurice S. Share, Camillus, N. Y., assignor to Camillus Cutlery Company, Inc., New York, N. Y., a corporation of New York

Application January 22, 1940, Serial No. 315,131

4 Claims. (Cl. 41—29)

This invention relates to the art of manufacturing ornamental faceplates primarily for penknives and the like and in which the faceplates are provided with one or more offset areas and 5 with an ornamental coating applied to the remaining area thereof.

The invention contemplates a method of manufacturing faceplates of the indicated character which utilizes mating die members having a 10 punch and punch receiving recess for offsetting a portion of the plate and for simultaneously cutting out a portion of a masking sheet having a gummed surface and causing the said portion to adhere to the plate whereby upon removal of 15 the remaining portion of the masking sheet a decorative coating may be applied to the unmasked portion of the plate while the masked portion remains uncoated.

More particularly the invention includes the 20 steps of interposing a gummed masking sheet or tape between die members having a punch and a mating punch receiving recess respectively corresponding to the contour of the area of the faceplate to be offset, disposing a blank faceplate 25 between the masking sheet and the adjacent die member with the gummed surface thereof disposed next to said plate, forcing said die members together to effect the offsetting of a portion of said plate and to cut out a corresponding portion of 30 said masking sheet and press the gummed surface thereof into engagement with the offset portion, removing the remaining portion of said sheet from said plate and applying a decorative coating to the unmasked portion of said plate and 35 subsequently removing the cut-out portion from said plate.

With the above recited and other objects in view, the invention is set forth in greater detail in the following specification and illustrated in 40 the accompanying drawing.

In the drawing:

Fig. 1 is an enlarged vertical sectional view through the offsetting die members and through the faceplate and masking sheet illustrating the 45 same in juxtaposition prior to the offsetting of the faceplate and the cutting out and applying of a portion of the masking sheet to the faceplate.

Fig. 2 is a similar view illustrating the step of 50 offsetting the faceplate and cutting out and adhesively bonding a portion of the masking sheet to the offset portion of the faceplate.

Fig. 3 is a similar view illustrating the retracted relation of the die members after the off- 55 setting operation and showing the cut-out por-

tion of the masking sheet adhering to the offset portion thereof.

Fig. 4 is a horizontal sectional view on a reduced scale taken approximately on the line 4—4 of Fig. 1.

Fig. 5 is a sectional view on an enlarged scale of the faceplate after the offsetting operation with the portion of the masking sheet applied to the offset portion and illustrating the manner in which the coating is applied to the unmasked 10 portion thereof.

Fig. 6 is a similar sectional view illustrating the finished faceplate with the coating applied and with the portion of the masking tape removed.

In carrying the method into practice, suitable offsetting die members 10 and 11 are employed, the latter being in the form of a fixed block having an opening 12 extending vertically therethrough which may be of any desired cross sectional shape corresponding to the contour of the offset portion to be produced on the faceplate 13. The lower terminal of the upper movable die member 10 has a cross sectional shape corresponding to the cross sectional configuration of the opening 12 and of slightly smaller size. As illustrated, the lower die member or block 11 has arranged and fitted within the opening 12 a yieldable elastic or resilient core 14, such as rubber or an equivalent material. The die member 10 may be operated in any suitable manner to advance the same towards and retract the same from the fixed die member 11, such as by positioning the die members in a punch press.

In carrying out the method, a masking sheet 15 which is preferably in the form of a tape having an adhesive or gummed surface of a type which adheres upon contact and pressure is employed. In operation, the masking sheet or tape 15 with the adhesive or gummed surface disposed upward is fed between the upper and lower die members 10 and 11 as illustrated in Fig. 1 of the drawing. The face plate 13 is interposed between the upper gummed or adhesive surface of the tape and the lower end of the upper die member. The upper die member 10 is then forced downwardly, as illustrated in Fig. 2 to effect the offsetting or embossing of a portion of the face plate as at 16. This simultaneously cuts out a corresponding portion 17 of the masking tape or sheet 15 which is caused to adhere to the offset portion 16 by virtue of the pressure exerted thereon as the yieldable core 14 is depressed in the opening 12 of the lower fixed die member 11. When the upper die member 10

is retracted, as illustrated in Fig. 3 of the drawing, the face plate may then be removed with the cut-out portion 17 of the masking sheet or tape 15 adhering to the offset portion 16. The 5 face plate with the cut-out portion 17 of the masking sheet adhesively connected to the offset portion 16 is then coated by spraying or otherwise applying the coating material to the unmasked area of the surface, while the portion 10 17 prevents the coating of the material from being applied to the offset portion 16. After the coating operation, the portion 17 of the masking sheet is removed thereby producing an ornamental face plate having a coated surface area 15 19 and an offset uncoated surface area 16.

For the purpose of illustrating the carrying out of the method, the same is described for providing an ornamental face plate with a single offset area and a coated area surrounding the 20 offset area and between the bolster ends 18 of the face plate. It is within the purview of the invention that one or more areas may be simultaneously offset, such as the offset area 16 and the bolster ends 18 by utilizing appropriate die 25 members and a sheet or strip of gummed masking tape of a width to accommodate the entire length of the face plate.

What is claimed is:

1. A method of manufacturing ornamental 30 face plates for penknives and the like including interposing a gummed masking sheet between offsetting die members, disposing a blank face plate between the gummed masking sheet and the adjacent die member with the gummed surface thereof disposed next to said plate, forcing said die members together to punch said sheet to produce an offset portion therein and cut out a portion of said masking sheet and press the gummed surface of a portion of said masking 35 sheet into engagement with the plate, removing the unsecured portion of said sheet, applying a decorative coating to the unmasked portion of the face of said plate and subsequently removing the cut-out portion therefrom.

2. A method of manufacturing ornamental face plates for penknives and the like including interposing a gummed masking strip between offsetting die members, disposing a blank face plate between the gummed masking strip and the adjacent die member with the gummed surface thereof disposed next to said plate, forcing said die members together to offset a portion of said plate and cut-out a corresponding portion of said masking sheet and press the gummed surface thereof into engagement with the offset portion, removing the remaining portion of said sheet, applying a decorative coating to the unmasked portion of the face of said plate and subsequently removing the cut-out portion 15 therefrom.

3. A method of manufacturing ornamental face plates for penknives and the like including interposing a gummed masking strip between offsetting die members, disposing a blank plate 20 between the masking strip and the adjacent die member with the gummed surface of said strip disposed next to said plate, forcing said die members together to offset a portion of said plate and simultaneously cut-out a corresponding portion 25 of said masking strip and press the gummed surface thereof into engagement with the offset portion, removing the remaining portion of said strip from said plate, applying a decorative coating to the unmasked portion of the face of 30 said plate, and subsequently removing the cut-out portion from said offset area.

4. A method of producing ornamental face plates having a coated surface area and an offset uncoated surface area, said method consisting in effecting the offsetting of said surface area and coincident therewith, cutting out from and adhesively bonding to the offset surface area a portion of an adhesive masking sheet so as to cover said offset area, applying the coating to the 40 unmasked area of the face plate and then removing the adhesively applied portion of the masking tape from the face plate.
